UNITED STATES PATENT OFFICE

157,805

BOBBY PIN OPENER

Joseph A. Voss, Denver, Colo.

Application June 24, 1949, Serial No. 3,494

Term of patent 3½ years

(Cl. D86—10)

To all whom it may concern:

Be it known that I, Joseph A. Voss, a citizen of the United States, residing at Denver, State of Colorado, have invented a new, original, and ornamental Design for a Bobby Pin Opener, of which the following is a specification, reference being had to the accompanying drawing, forming a part thereof.

I claim:

The ornamental design for a bobby pin opener, as shown.

JOSEPH A. VOSS.
